No. 36,824.

Patented February 23, 1904.

UNITED STATES PATENT OFFICE.

FREDERICK W. GRELL, OF NEW YORK, N. Y., ASSIGNOR TO AMERICAN HARD RUBBER COMPANY, OF NEW YORK, N. Y., A CORPORATION OF NEW YORK.

DESIGN FOR A COMB.

SPECIFICATION forming part of Design No. 36,824, dated February 23, 1904.

Application filed December 29, 1903. Serial No. 187,071. Term of patent 14 years.

To all whom it may concern:

Be it known that I, FREDERICK W. GRELL, a citizen of the United States, residing at New York city, State of New York, (post-office address, No. 9 Mercer street, borough of Manhattan, city and State of New York,) have invented a new, original, and ornamental Design for Combs, of which the following is a specification, reference being had to the accompanying drawings, forming a part thereof, in which—

Figure 1 is a side elevation of one form of comb, showing my new design; and Figs. 2 and 3 are sections, respectively, on line 22 and 33, Fig. 1.

15

What I claim, and desire to secure by Letters Patent, is—

The new, original and ornamental design for a comb as herein shown.
